UNITED STATES PATENT OFFICE.

DAVID H. HUNTER, OF DALLAS, TEXAS, ASSIGNOR TO SULLIVAN MACHINERY COMPANY, A CORPORATION OF MASSACHUSETTS.

PUMPING SYSTEM.

Application filed May 14, 1923, Serial No. 638,692. Renewed October 2, 1924.

My invention relates to pumping systems, and more particularly to automatically controlled starting systems for air lift pumping mechanisms.

5 An object of my invention is to provide an improved air lift pumping mechanism. Another object of my invention is to provide an improved automatic control for the starting jet which is used in some kinds of 10 air lift pumping systems.

It is no uncommon thing in practice to encounter wells whose normal or idle water level is above, by a very material height, the level which the liquid flow will maintain 15 during the regular pumping of the well, and in wells of this nature it frequently happens that if the well has not been pumped for some time the head of water above the foot piece may be so great that the static head 20 will be in excess of the available air pressure. In wells of this type it is customary to employ an auxiliary or starting jet arranged a substantial distance above the bottom of the well, this jet being used, so to 25 speak, to blow off the excess head so that the main jet may be able to discharge and then carry on the regular pumping. It is not desirable ordinarily that the auxiliary or starting jet remain in operation after the 30 conditions become such that the main jet can assume the work and accordingly various means for controlling the auxiliary jet have been devised. It is, particularly, the object of my invention to provide an improved 35 automatic control for such a starting or auxiliary jet. Other objects and advantages of my improvement will, however, herein-after more fully appear.

In the accompanying drawings I have 40 shown for purposes of illustration one form which my invention may assume in practice.

In these drawings,—

Fig. 1 is a view partially in side elevation and partially diagrammatic showing the 45 general arrangement of the system.

Fig. 2 is an enlarged detail view in central vertical section through the control mechanism per se.

Fig. 3 is a detailed section on a still further enlarged scale taken on the line 3—3 of 50 Fig. 2.

Fig. 4 is a section on the line 4—4 of Fig. 1.

In the illustrative embodiment of my invention a compressor 1 is shown discharging

by way of a pipe 2 to a receiver 3. From the receiver 3 a pipe 4 leads off. This pipe is branched and the valve-controlled branch 5 thereof extends down to a foot piece 6 arranged at the bottom of a riser pipe 6' 60 which at its upper end terminates in a tank 7 from which a pipe 8 leads off to any desired point of discharge. The other branch of the pipe 4 is also valved and is numbered 9 and connects, under the control of a valve 65 mechanism generally designated 10, with a pipe 11 leading to an auxiliary jet 12 arranged within the riser pipe 6' at a substantial distance above the bottom of the well, but materially below the level to which 70 the liquid will rise when the well fills up in the intervals between pumping. It will be observed that the valve mechanism 10 comprises a casing 13 in which a conical bore 14 is provided and within this bore a hollow 75 conical valve 15 is rotatable, the valve 15 at its open end communicating with the pipe 9 while through a port 16 therein and a port 16' in the casing 13 fluid is adapted to be supplied to the pipe 11. It will be observed 80 that the valve 15 extends through the end of the casing 13 and is provided with a squared stem 17 upon which a sprocket wheel 18 is secured.

Within the tank there is provided a usual 85 umbrella top against which the mixture of air and liquid discharged through the riser pipe 6' impacts and which serves to direct the liquid back toward the bottom of the tank. This umbrella which is numbered 20 90 is supported by suitable elements 21 upon a collar 22 at the top of the riser pipe 6'. Arranged adjacent the top of the tank 7 is an open topped casing 23 in which a bucket 24 is slidably, this bucket being mounted upon 95 a vertically reciprocable rod 25 which is guided in guide members 26 and 27 projecting in radially from the sides of the casing member 23. It will be noted that the bottom of the casing member 23 freely communicates through a passage 28 with the tank 7 while the top also communicates through a short piece of pipe 29 with the interior of the top of the tank 7. Secured to the pipe 29 within the interior of the tank 100 is a grooved trough-like member 30 which projects upwardly and over so that it extends just inside the rim of the depending portion of the umbrella and so that it receives a small portion of the liquid which 105 110

strikes the umbrella and deflects it into the pipe 29 through which it flows into the casing 23 and falls into the bucket 24. The bucket 24 is provided with a small orifice 32 through which the liquid flows out, this orifice being somewhat smaller than the capacity of the deflecting member 30 and pipe 29 so that, although some of the liquid flows out of the bottom of the bucket and back into the tank 7, the bucket gradually fills if the pump is pumping enough water to keep the pipe 29 full. The orifices may be changed to vary the period of operation if desired. It will be noted that the rod 25 is connected to a suitable chain 33 which is adapted to cooperate with the sprocket wheel 18 and which passes over the latter and that the free end of the chain 33 has attached thereto a weight 34, the weight 34 being so selected that it will support the bucket until it is nearly full and will then be lifted by the combined weight of the bucket and the water contained in the latter. The sprocket wheel and chain are so arranged with respect to each other that at the time that the bucket is in top position the valve is wide open but when the bucket drops to a bottom position the valve is closed.

From the foregoing description the mode of operation of this mechanism will be readily apparent. Let it be assumed that it is desired to start the system and that the standing level of the liquid in the well is so high that the opening of the valve controlling the pipe 5 does not result in the starting of any flow in the riser pipe 6'. This having been tested out, the valve controlling the pipe 9 will be opened and since the position of the valve 15 is then such with respect to the casing that the pumping fluid may freely flow through the ports 16 and 16' to the pipe 11, fluid will pass to the auxiliary jet 12 and will start to pump the well. The liquid rising in the riser pipe 6' will discharge against the umbrella and in part will be intercepted by the deflector 30 and will be connected thereby and by the pipe 29 to discharge into the bucket 24. During the starting of the well it may be that the quantity of liquid raised by the single jet will not be so great that the quantity passing into the bucket cannot flow out and back into the tank 7, but on the pumping down of the liquid to a sufficient extent to permit the foot piece 6 to become operative the discharge will be considerably amplified and in a short time the quantity of liquid intercepted by the deflector 30 from this greater flow will fill the bucket and accordingly cause the valve 15 to be moved to interrupt the supply of fluid to the auxiliary pumping jet. It will be understood that the foot piece 6 is so operated as to maintain during the pumping of the well a flow of such magnitude that the bucket will be constantly maintained in de-

pressed position and so that the valve 15 will be maintained closed throughout the entire remaining period of pumping operation. It is unnecessary that the parts be designed exactly as specified, it being evident that if 70 desired the opening 32 may be so proportioned that the bucket will become filled just after the surplus head is pumped off and without having to have any substantial overlap between the operations of the two jets, 75 but as it is somewhat difficult to precisely gage the period during which starting discharge may be necessary, the system of operation first described is probably preferable from a practical standpoint. 80

While I have in this application described one form which my invention may assume in practice, it will be understood that this form of the same is shown for purposes of illustration and that the invention may be 85 modified and embodied in various other forms without departing from its spirit or the scope of the appended claims.

What I claim as new and desire to secure by Letters Patent is:

1. In combination, a fluid actuated pumping mechanism, and means for controlling the same including a rotatable valve and actuating means for said valve operated by a portion of the liquid discharging from 95 said pumping mechanism.

2. In combination, in an air lift pumping mechanism comprising a riser pipe, a foot piece, and a starting jet, means for controlling said jet including a rotatable valve, and means operated by a portion of the liquid flowing in the riser for closing said valve.

3. In an air lift pumping mechanism, a pump, a tank to receive the discharge thereof, and means for controlling said pump including a receptacle and means for effecting the control of said pump disposed in said receptacle and made operative by a flow of fluid diverted from the discharge flow.

4. The combination in an air lift pumping system comprising a riser pipe, a foot piece, a starting jet, means for controlling said jet including a valve, a tank adapted to receive the discharge from said riser pipe, 115 a relatively stationary receptacle, and means cooperating with said receptacle and operated by a portion of the liquid flowing in the riser for closing said valve.

5. In an air lift pumping system, in combination, a riser pipe, a tank receiving the discharge therefrom, main and auxiliary jets associated with said riser pipe, a receptacle, and a liquid actuated member associated therewith for controlling said auxiliary jet.

6. In an air lift pumping system, in combination, a riser pipe, a tank receiving the discharge therefrom, main and auxiliary jets associated with said riser pipe, and 130

means including a receptacle and a liquid actuated receiving member associated therewith for controlling said auxiliary jet and adapted to discharge into said receptacle.

5 7. In an air lift pumping system, in combination, a riser pipe, a tank receiving the discharge therefrom, main and auxiliary jets associated with said riser pipe, a receptacle, and a liquid actuated member associated therewith for controlling said auxiliary jet and adapted to have communication with said receptacle and tank.

10 8. In an air lift pumping mechanism comprising a riser pipe, a tank receiving the discharge therefrom, and main and auxiliary jets associated with said riser pipe, means for controlling said auxiliary jet including a vessel supported by said tank, a vessel slideable in said first mentioned vessel and 15 having a perforated bottom, means connecting the bottom of said first mentioned vessel with the interior of the tank, means for conducting a portion of the liquid raised in said riser pipe to said second mentioned vessel, and a valve controlling the air supply to the auxiliary jet controlled by movement of said second mentioned vessel.

20 9. In an air lift pumping mechanism comprising a riser pipe, a tank receiving the discharge therefrom, and main and auxiliary jets associated with said riser pipe, means for controlling said auxiliary jet including a vessel supported by said tank, a vessel slideable in said first mentioned vessel and 25 having a perforated bottom, means connecting the bottom of said first mentioned vessel with the interior of the tank, means for conducting a portion of the liquid raised in said riser pipe to said second mentioned vessel,

a valve controlling the air supply to the auxiliary jet controlled by movement of said second mentioned vessel, and means including a rotatable member connected to said valve and a member connected to said second mentioned vessel and cooperating with said rotatable member to transmit movement thereto.

40 10. In an air lift pumping mechanism comprising a riser pipe, a tank receiving the discharge therefrom, and main and auxiliary jets associated with said riser pipe, means for controlling said auxiliary jet including a vessel supported by said tank, a vessel slideable in said first mentioned vessel and having a perforated bottom, means connecting the bottom of said first mentioned vessel with the interior of the tank, means for conducting a portion of the liquid raised in said riser pipe to said second mentioned vessel, a valve controlling the air supply to the auxiliary jet controlled by movement of said second mentioned vessel, and means including a rotatable toothed member connected to said valve and a member connected at one end to said second mentioned vessel at its other end to a weight and cooperating with said toothed member to transmit movement thereto.

45 11. In an air lift pumping mechanism, in combination, a riser pipe, a tank receiving the discharge therefrom, main and auxiliary jets associated with said riser pipe, and means including a liquid actuated member arranged outside said tank for controlling said auxiliary jet.

50 In testimony whereof I affix my signature.

DAVID H. HUNTER.
